(57) **CLAIM**

We claim the ornamental design for a handheld electronic device shell, as shown and described.

DESCRIPTION

FIG. 1 is a front perspective view of a handheld electronic device shell;

FIG. 2 is a back perspective view of the handheld electronic device shell;

FIG. 3 is a front elevational view thereof;

FIG. 4 is a back elevational view thereof;

FIG. 5 is a right elevational view thereof;

FIG. 6 is a left elevational view thereof;

FIG. 7 is a top plan view thereof; and,

FIG. 8 is a bottom plan view thereof.

The broken lines in the drawings of the handheld electronic device shell are for illustrating unclaimed features of the article and form no part of the claimed design.
